United States Patent Office

Des. 206,854
Patented Feb. 7, 1967

206,854

BRASSIERE

Charles M. Sachs, Fort Lee, N.J., assignor to International Latex Corporation, Dover, Del., a corporation of Delaware

Filed May 6, 1964, Ser. No. 79,838

Term of patent 14 years

(Cl. D2—24)

The figure is a front plan view of a brassiere showing my new design.

I claim:

The ornamental design for a brassiere, as shown.
